US00D487111S

(12) **United States Design Patent** (10) Patent No.: **US D487,111 S**
Rosenbaum (45) Date of Patent: ** Feb. 24, 2004

(54) **WRITING INSTRUMENT**

(75) Inventor: **Barry Rosenbaum**, West Bloomfield, MI (US)

(73) Assignee: **Advance Watch Company, Ltd.**, Warren, MI (US)

(**) Term: **14 Years**

(21) Appl. No.: **29/183,237**

(22) Filed: **Jun. 9, 2003**

Related U.S. Application Data

(62) Division of application No. 29/147,280, filed on Aug. 24, 2001, now Pat. No. Des. 477,022.

(51) **LOC (7) Cl.** **19-06**

(52) **U.S. Cl.** **D19/36; D19/46; D19/51**

(58) **Field of Search** **D19/35, 36, 41-51, D19/53-58, 75, 81-85; 401/6, 7, 88, 52, 195, 209**

CLAIM

The ornamental design for a writing instrument, as shown and described.

DESCRIPTION

FIG. 1 is a top perspective view of the first embodiment of the writing instrument of this invention;

FIG. 2 is a right side elevational view of the first embodiment of the writing instrument of this invention, the left side elevational view being a mirror image thereof;

FIG. 3 is a top elevational view of the first embodiment of the writing instrument of this invention;

FIG. 4 is a bottom elevational view of the first embodiment of the writing instrument of this invention;

FIG. 5 is a bottom plan view of the first embodiment of the writing instrument of this invention;

FIG. 6 is a top plan view of the first embodiment of the writing instrument of this invention;

FIG. 7 is a top perspective view of the second embodiment of the writing instrument of this invention;

FIG. 8 is a right side elevational view of the second embodiment of the writing instrument of this invention, the left side elevational view being a mirror image thereof;

FIG. 9 is a top elevational view of the second embodiment of the writing instrument of this invention;

FIG. 10 is a bottom elevational view of the second embodiment of the writing instrument of this invention;

FIG. 11 is a bottom plan view of the second embodiment of the writing instrument of this invention; and,

FIG. 12 is a top plan view of the second embodiment of the writing instrument of this invention.

The portions of the writing instrument depicted by means of broken lines have been shown for illustrative purposes only and form no part of the claimed design.
